UNITED STATES PATENT OFFICE.

HENRY HARDISTY, OF TUALATIN, OREGON.

DESIGN FOR A RADIATOR CAP OR SIMILAR ARTICLE.

Application filed June 20, 1921. Serial No. 479,135. Term of patent 3½ years.

To all whom it may concern:

Be it known that I, HENRY HARDISTY, a citizen of the United States, residing at Tualatin, in the county of Washington and State of Oregon, have invented a new, original, and ornamental Design for a Radiator Cap or Similar Article, of which the following is a specification, reference being had to the accompanying drawing, forming part thereof.

The single figure of the drawing is an elevation, showing my new design.

I claim:—

The ornamental design for a radiator cap or similar article, substantially as shown.

In testimony, that I claim the foregoing as my own, I have hereto affixed my signature.

HENRY HARDISTY,
